UNITED STATES PATENT OFFICE.

JOHN ERNEST MOORE, OF BLACKBURN, ENGLAND.

ADJUSTABLE THREAD-SELECTING DEVICE.

Application filed April 18, 1924. Serial No. 707,422.

To all whom it may concern:

Be it known that I, JOHN ERNEST MOORE, a subject of the King of Great Britain and Ireland, residing at Eanam, Blackburn, in the county of Lancaster, England, have invented certain new and useful Improvements in Adjustable Thread-Selecting Devices, of which the following is a specification.

10 This invention relates to selector needles for use in connection with apparatus such for example as that which is described in Patent Specification Number 1,259,546 for selecting and separating warp threads and 15 has for its chief object to construct a needle of this class in such a manner that it will have a bigger range of action than other needles as hitherto constructed. These needles are formed with a notch or recess 20 at one side to take the warp thread, or a number of warp threads, the size of the notch being determined by the thickness of the warp thread, or the number of threads that the needle has to take. Machines in 25 which these needles are used are capable of dealing with warps of different thicknesses and for some classes of work it is necessary to select only one thread at a time whereas for other classes of work it may be necessary 30 to select two or more threads at a time. This can only be done at present by using a needle that has the correct size of notch for the particular purpose in hand. If another warp having a different size of warp 35 threads is introduced into the machine or it is required to select a different number of warp threads at a time it becomes necessary to substitute another needle with the correct size of notch to suit the change that has 40 been made.

According to this invention the needle is provided with a movable member by adjustment of which the size of the notch can be regulated to suit various classes of work which come within the scope of the machine in which the needle is to be used. A feature of the invention consists in mounting the needle in its holder in such manner that it can be secured without the use of a 45 clamping screw and can be instantly inserted and removed as and when required.

In the accompanying drawings:—

Fig. 1 is a plan of a needle and holder constructed in accordance with this invention.

Fig. 2 is a similar view to Fig. 1 show-

ing a different position of the part which constitutes the notch.

Fig. 3 is an edge view of the needle, a portion of the carrier being indicated by the broken lines, and

Fig. 4 shows a modified construction of needle.

A indicates the needle, and B the carrier or holder.

In the construction shown the needle A is slotted at a to receive a thin plate a^1 which is pivotally mounted at a^2 in the slot a . The front end of this plate crosses the slot in a slanting direction and its rear end is 65 operatively connected with a screw a^3 which passes transversely through the needle, the arrangement being such that when the screw is turned in one direction or the other, it 70 imparts a turning movement to the plate 75 about its pivot. When the plate is moved to the extreme limit in one direction by the adjusting screw, the point of the slanting end of the plate lies within the slot, or comes 80 flush with the side of the needle as shown 85 in Fig. 2. If the adjusting screw a^3 is now turned in the opposite direction it causes the point of the slanting end to project through the slot so that it stands out at one 90 side of the needle and forms the notch as 95 shown in Figs. 1 and 4, the amount which such slanting end does project from the side of the needle being capable of regulation from nothing to any predetermined extent. When the plate has been adjusted to produce the required size of notch it can be secured in its adjusted position by a clamping screw a^4 which passes through the needle and through a slot a^5 in the plate. Instead of the needle being slotted to receive the plate, the latter may be pivotally 100 mounted on the side of the needle as shown in Fig. 4.

Any other appropriate construction can be used for imparting lateral movement to the plate for regulating the size of the notch, for example the plate can be arranged to be moved in an endwise direction by a nut or screw or other propelling device so that as its slanting end is forced against the end 105 of the slot, it will be displaced in an outward direction, its return movement being effected by a spring, or other device, when the propelling means is moved in the opposite direction. If desired the plate itself 110 may constitute a spring so constructed that the slanting end tends to project outwardly

to one side of the needle and is forced inwardly to produce a notch of the required size by sliding or screwing a ring along the needle.

5. It is to be understood that these modifications are given by way of example only, the main feature of the invention consisting in the introduction to a selector needle of an adjustable notch that can be varied in size, 10 to meet any particular requirement.

A simple contrivance for attaching the needle A to the carrier or holder B comprises a spring b that is attached to the carrier and enters a notch b¹ or hole in a portion 15 of the carrier and another notch a² that is formed in the needle. With this construction the needle can be pushed into position or pulled out of the carrier as and when required, the spring b yielding during these 20 movements and being sufficiently strong to retain the needle in position against accidental displacement when the machine is in operation. If desired more than one notch may be formed in the needle to enable its 25 position in the holder to be adjusted.

What I claim as my invention and desire to secure by Letters Patent in the United States, is:—

1. A thread selecting device, comprising 30 a guide needle, a flat plate pivoted at its front end portion to the guide needle and having a pointed front end portion adapted

to be adjusted so as to project above the level of one side of the guide needle, a notch being thereby formed by said needle and plate between the pivot of the plate and the point of the needle, and means for clamping the plate to the guide needle.

2. A thread selecting device as set forth in claim 1, and provided with a screw for 40 moving the plate pivotally to adjust it.

3. A thread selecting device comprising a guide portion, a plate pivoted to it and shaped at its front end to form a barb or ledge projecting from the guide portion, an adjusting screw mounted in the guide portion and arranged to cooperate with the plate in such manner as to turn the latter about its pivot, and a clamping screw mounted in the guide portion and passing 45 through a slot formed in the plate.

4. A thread selecting device comprising a guide portion recessed near its rear end, a plate pivoted to the guide portion and shaped at its front end to form a barb or ledge projecting from the guide portion near its front end, a carrier formed with a socket to receive the rear end of the guide portion, a spring mounted on the carrier and adapted to interlock with the recess in 55 the guide portion.

In testimony whereof I affix my signature.

JOHN ERNEST MOORE.
